UNITED STATES PATENT OFFICE.

EDGAR ABBOTT, OF BOSTON, MASSACHUSETTS.

EMERGENCY SHUT-OFF FOR SPRINKLER-HEADS.

No. 845,918.

Specification of Letters Patent.

Patented March 5, 1907.

Application filed October 2, 1905. Serial No. 280,917.

To all whom it may concern:

Be it known that I, EDGAR ABBOTT, of Boston, in the county of Suffolk and State of Massachusetts, have invented a new and useful Emergency Shut - Off for Sprinkler-Heads, of which the following is a specification.

My invention relates to that class of sprinkler-heads in which the sprinkling is normally prevented by a thermostat supported by the head and the thermostat is removed by the action of undue heat which melts the solder, whereupon the sprinkling is done automatically. After the fire which caused the heat has been extinguished it is desirable to stop the sprinkling without waiting to shut off the valve which controls the sprinkler-system, as such shutting off will often require a considerable time and consequent damage by unnecessary sprinkling.

The object of my invention is to provide a shut-off for the sprinkler-head to be used at such times and which can be readily inserted in the sprinkler-head and locked against movement tending to open the sprinkler and yet easily unlocked and removed, and which is adjustable for various sizes and styles of sprinkler-heads, and which will be simple in construction and practical in operation both as to its shutting-off function and as to its locking and unlocking.

My invention consists in such a shut-off comprising two members which are connected but movable relatively one member to close the sprinkler-aperture and the other to bear against an abutment of the sprinkler-head and means to lock the two members against such relative movement as would tend to open the sprinkler.

A feature of my invention consists in means for locking the two members in the desired position for different sizes of sprinkler-head.

45 A third feature consists in means for locking and unlocking the members without relative movement of them.

Other features of my invention are herein-after described.

50 In the drawings, Figure 1 is an elevation of my shut-off in place in the sprinkler-head. Fig. 2 is a vertical section of the same, showing the handle. Fig. 3 is a section of the shut-off itself with the handle partly in ele-

vation. Figs. 4 and 5 are details described below.

The sprinkler-head A has water-aperture a and arch a', in which at its lower portion is mounted adjustable abutment a².

Pivoted to handle member A' is shank 60 member B, which is threaded at both ends b, but which has a central portion b', which is not threaded. The cap or stopper B' is internally threaded to engage the threaded portions of the shank member B. The screw b² passes through the cap B' and lies between the threaded portions of the shank B, limiting the motion of the cap B' in both directions. The portion of the cap B' which closes the aperture of the sprinkler-head is preferably spherical, as shown at b³, and the cap is preferably roughened to permit of its being turned by a wrench. Lock-nut D is internally threaded for engagement with the lower thread of shank member B and is roughened at its outer surface to permit of its being turned by a wrench or the like. Handle member A' is pivoted at a³ to shank member B and has recess a¹¹ at the front portion of its lower face for engagement with the abutment a² of the sprinkler-head, and I have shown it also grooved at a⁵ in Figs. 4 and 5, and the object of this is that I may use my device with different forms of sprinkler-heads, the longitudinal abutment a⁶ being shown in Fig. 5. The front portion of the handle is U-shaped to receive the lower end of shank member B and forms a support for the lower part of the shank. The upper front portion a⁷ of the handle is of any suitable shape to form a bearing for the lock-nut when the device is locked.

In using my shut-off it is inserted in the sprinkler-head, the cap having been adjusted appropriately for the particular sprinkler-head, and the lower groove or recess in the handle engages the abutment at the bottom of the sprinkler-head. By swinging the handle A' the two members are moved relatively, one to close the water-aperture and the other to engage the abutment. The lock-nut is then rotated until it bears against the upper surface of the handle, and the shut-off is securely locked in position, stopping the sprinkling and preventing the flow of water until it is shut off at the source of supply, when my shut-off can be readily removed by turning the lock-nut in the re-

verse direction, permitting the ready removal of the shut-off. It will now be clear that when the two members, which I have called the "shank" member and the "handle" member, have been moved relatively to bear upon the abutment and to effectually shut off the water they are locked positively against relative movement tending to open the sprinkler, because the lock-nut prevents swinging of the handle, and this locking is accomplished without any relative movement of the two members, and the consequence is that no leakage can occur, because the shut-off is not moved after it is in the proper position to stop the flow of water. It will also be clear that the two members of my shut-off may by suitable relative movement be adjusted for the desired size of sprinkler-head and effectually locked in such adjustment.

What I claim is—

1. An emergency shut-off for sprinkler-heads of the character described comprising a handle member to engage the abutment; a valve member directly connected to the handle member but movable relatively to it; and means mounted on one of said members and movable into engagement with the other of said members for locking them when in position against relative movement.
2. An emergency shut-off for sprinkler-heads comprising a handle member, a valve member comprising a rod pivoted to said handle member, and a valve adjustable on said rod, and a device carried by said pivoted rod and movable into engagement with

said handle member to lock the said rod from turning on its pivot, substantially as described.

3. An emergency shut-off for sprinkler-heads comprising a handle member adapted to engage the abutment of the sprinkler-head, a valve member comprising a threaded rod pivoted to the handle member, and a valve having screw-threads to engage said thread-rod, and a nut in threaded engagement with said rod between said valve and said handle, said nut engaging said handle when the said rod is to be locked against turning on its pivot, substantially as described.

4. An emergency shut-off for sprinkler-heads of the character described comprising a handle member to engage the abutment, a valve member pivoted to said handle member, and means mounted on the valve member and movable into engagement with the handle member for locking the valve member from turning on its pivot.

5. An emergency shut-off for sprinkler-heads comprising a handle member, a valve member comprising a rod pivoted to said handle member, and a device carried by said pivoted rod and movable into engagement with said handle member to lock the said rod from turning on its pivot, substantially as described.
